ATTORNEY

UNITED STATES PATENT OFFICE.

OTTO H. ELLER, OF NEW YORK, N. Y.

FLYING TOY.

1,385,073.

Specification of Letters Patent.

Patented July 19, 1921.

Application filed November 22, 1919. Serial No. 339,806.

To all whom it may concern:

Be it known that I, OTTO H. ELLER, a citizen of the United States, residing in the city of New York, county of New York, and State of New York, have invented certain new and useful Improvements in Flying Toys, of which the following is a full, clear, and exact description, such as will enable others skilled in the art to which it pertains to make, construct, and use the same, reference being had to the accompanying drawings, and to numerals of reference marked thereon, forming a part of this specification.

The present invention relates to improvements in flying toys; and the object of my invention is to provide a device of exceedingly simple, efficient and inexpensive construction, which in addition to being used as a flying toy may be used as a spinning top.

My present invention therefore consists in the novel construction of a flying toy and top embodying the principles herein above mentioned, and of a character to be more fully described in the specification. This invention consists furthermore in the several novel arrangements and combinations of parts, as well as in the details of construction of the same, all of which will be herein set forth and then finally embodied in the clauses of the claim which are appended to this specification.

Reference is to be had to the accompanying drawings, forming a part of this specification in which similar reference characters indicate corresponding parts in all of the views.

Figure 1 represents, a side elevation of the flying toy embodying my invention.

Fig. 2 represents, a sectional elevation.

Fig. 3 represents, a side elevation of the device when used as a spinning top, and

Fig. 4 represents, a plan view of the apertured disk provided with diametrically oppositely arranged teeth.

In the drawings, 1 represents a barrel provided with a longitudinally arranged bore for the reception of the spirally wound spring 2 one end of which is secured in any desired or convenient manner to the lower end of the barrel as at 3 and the upper or free end of the spring is provided with a vertical offset 4 which extends slightly above the upper end of the barrel 1.

Secured to the top of said barrel in any desired or convenient manner, as for in-

stance by means of nails 5, is an apertured disk 6 preferably of metal the peripheral portions of which, at diametrically opposite sides are slotted and the metal adjacent said slots is thrown up so as to provide diametrically oppositely arranged teeth 7-7 to be engaged by the pin 8 which is secured to the rod 9 to be presently described.

The rod 9 which extends longitudinally through the spring 2 is adapted to freely turn therein, when in the position indicated in Figs. 1 and 2 of the drawings, and has secured to its upper end a head 10.

On the upper side of the head 10 are secured two diametrically oppositely arranged pins or studs 12 designed to engage with suitable apertures (not shown) in the propeller 14 which serve to position the propeller on said head.

When the device is to be used the spring is wound up by grasping the barrel 1 in one hand and turning the head 10 with the other hand. This causes the pin 8 to engage with the free end 4 of the spring 2, and the rod 9 is held in the right relation to the barrel and the spring held wound up by means of the pin 8 which engages with the teeth 7-7 on the apertured disk 6.

To project the device and cause the propeller to fly the operator simply pushes up slightly with his thumb or finger on the free end of the rod 9, in the direction indicated by the arrow, Fig. 1, which projects through the lower end of the barrel, thus causing the pin 8 to clear the teeth 7-7 and the up-turned end 4 of the spring 2, thus causing the spring to give a quick impulse to the rod 9, with its attached head and propeller and rapidly to rotate it, thereby releasing the propeller from the pins 12 permitting the same to grip the air and rise.

When the toy is intended to be used as a top, instead of a flying toy, the propeller is discarded and the conical head 15 is substituted therefor. The conical head is provided on its under side with apertures designed to receive the pins 12-12 of the head 10, and is further provided with a stem 16 designed to fit into the aperture 17 of the head 10. In this manner the conical head 15 is removably secured upon the head 10. After the toy has been wound up in the manner above described, the same instead of being held upwardly into the air, is turned downwardly so that when the rod 9 with its attached parts is released from the barrel

the same will strike the floor and spin on the pointed end of the conical head 15.

Experience has demonstrated that the organization above described is a highly efficient one, and while I have shown the preferred embodiment of my present invention, I do not wish to be limited to the exact details of construction shown and described, as obvious modifications thereof, not involving the exercise of invention, as for instance changing the configurations or shapes of the various parts may be made by any skilled mechanic, and such departures from what is herein set forth, I consider within the scope 10 and terms of my claims.

Having thus fully described my invention, what I desire to secure by Letters Patent, is:—

1. An apparatus of the kind described, comprising a barrel provided with a longitudinally arranged bore, a spiral spring located within the bore of said barrel, one end of which is secured to one end of said barrel and the other end of which extends above the 25 other end of said barrel, a rod provided with a head at one end, said rod extending longitudinally through the spring and barrel and adapted to turn loosely therein, diametrically oppositely arranged pins secured 30 in the said head, a propeller provided with

apertures designed to be engaged by said pins, detachably secured to said head, an apertured disk provided with diametrically oppositely arranged teeth secured to the top of the barrel, a pin passing through the rod and located below the head to be engaged by the said teeth on the apertured disk. 35

2. An apparatus of the kind described, comprising a barrel provided with a longitudinally arranged bore, a spring located 40 within the bore of said barrel, one end of which is secured to one end of said barrel and the other end of which extends above the other end of said barrel, a rod provided with a head at one end and a pin passing 45 through the rod and located below said head, said rod extending longitudinally through the spring and barrel and adapted to turn loosely therein, an apertured disk provided with diametrically oppositely arranged teeth 50 secured to the top of the barrel to be engaged by the said pin on the rod and means at the upper end of the rod for detachably engaging a flying projectile.

This specification signed and witnessed 55
this 13th day of November 1919.

OTTO H. ELLER.
